US00D855061S

(12) United States Design Patent (10) Patent No.: US D855,061 S
Krieter et al. (45) Date of Patent: * Jul. 30, 2019

(54) DISPLAY SCREEN WITH GRAPHICAL USER INTERFACE

(71) Applicant: Allstate Insurance Company,
 Northbrook, IL (US)

(72) Inventors: Dean Krieter, Rolling Meadows, IL (US); Salvador Lopez, Round Lake, IL (US); Christopher Trinco, Hoffman Estates, IL (US); Katherine Rose Swindler, Chicago, IL (US); Trina Uzee, Glenview, IL (US)

(73) Assignee: Allstate Insurance Company,
 Northbrook, IL (US)

() Term: 15 Years

(21) Appl. No.: 29/644,243

(22) Filed: Apr. 16, 2018

(51) LOC (11) Cl. 14-04
 (52) U.S. Cl. USPC D14/485

(58) Field of Classification Search

USPC D14/485-495
 CPC G06F 17/211; G06F 17/212; G06F 3/1251;
 G06F 3/0481; G06F 2203/04807

(57) CLAIM

The ornamental design for a display screen with graphical user interface, as shown and described.

DESCRIPTION

The FIGURE is a front view of a display screen with graphical user interface showing our new design.

The broken lines in the drawing illustrate portions of the display screen with graphical user interface that form no part of the claimed design.

1 Claim, 1 Drawing Sheet
